United States Patent Office

Des. 233,501

Patented Nov. 5, 1974

233,501

DISH

Walter Zeischedegg, 3 Neue Str., 79 Ulm, Germany

Filed Mar. 30, 1973, Ser. No. 346,636

Claims priority, application Germany Oct. 2, 1972

Term of patent 14 years

Int. Cl. D7—01

U.S. Cl. D7—1

FIG. 1

FIG. 2

FIG. 3

FIG. 6

FIG. 4

FIG. 5

FIG. 1 is a top perspective view of a dish embodying my novel design;

FIG. 2 is a perspective view thereof rotated through 60° with respect to the view of FIG. 1;

FIG. 3 is a top view thereof;

FIG. 4 is a bottom view thereof;

FIG. 5 is a side elevational view corresponding to FIG. 2; and

FIG. 6 is a cross-section taken generally along the line VI—VI of FIG. 3.

I claim:

The ornamental design for a dish, as shown.
